INVENTOR

Guy B. Fitz
By his attorney,
Nelson M. Howard

UNITED STATES PATENT OFFICE.

GUY B. FITZ, OF AUBURN, MAINE, ASSIGNOR TO FITZ-EMPIRE DOUBLE PIVOT LAST COMPANY, OF AUBURN, MAINE, A CORPORATION OF MAINE.

LAST WITH REINFORCED TOE.

Application filed July 16, 1919. Serial No. 311,220.

To all whom it may concern:

Be it known that I, GUY B. Fitz, a citizen of the United States, residing at Auburn, in the county of Androscoggin and 5 State of Maine, have invented certain Improvements in Lasts with Reinforced Toes, of which the following description, in connection with the accompanying drawings, is a specification, like reference characters on 10 the drawings indicating like parts in the several figures.

This invention relates to lasts for making boots and shoes.

It has been found necessary, in the case 15 of lasts having sharply pointed toes, to apply some form of reinforcement to the last at this point, as the unreinforced toe tip frequently breaks from various causes such as abuse, percussive contact with the leveling 20 machine roller and the like.

Various modes of reinforcement have been suggested, but they are all either incompletely effective to protect the toe tip, or are expensive to manufacture, or both. It is the 25 object of the present invention to provide a reinforcement which will be effective and cheap to manufacture.

A feature of the invention resides in a 30 metallic reinforcing piece constructed and arranged to be embedded in the last surface, preferably in a channel around the toe tip. In the illustrated last, this channel extends in a vertical plane, as I have found that structure most efficacious in avoiding damage.

Another feature consists in a last having 35 a metallic strip embedded in its surface and extending preferably around the toe tip, advantageously in a vertical plane.

Another feature of the invention resides in a last channeled in its surface to receive a reinforcing piece. Preferably holes are formed in the bottom of the channel leading into the body of the last to serve as anchorages for the reinforcing piece.

These and other features of the invention will be understood from the following description of a preferred embodiment thereof shown in the drawing in which,

Fig. 1 is a sectional view of the reinforcement.

Fig. 2 shows the last prepared for the reinforcement.

Fig. 3 shows the reinforcing strip,

Fig. 4 shows the sole of the last with the 55 reinforcement in place, and

Fig. 5 is a cross section of the reinforced toe.

The last to be reinforced may be of any type and is shown as a block last. The illustrated last is of ordinary construction except at the toe tip. It is channeled around the toe tip between points about $1\frac{1}{2}$ inches back of the tip, the channel running preferably in one plane from one point to the 60 other. The channel, shown at 10, is advantageously formed in a vertical plane, as shown, but the invention is not to be regarded as limited to vertical as distinct from, for example, horizontal reinforcement. 70

Holes 12, 14 are bored in the last at the extremities of the channel 10, respectively, and a rod or piece of wire, preferably in the form of a flat ribbon, is suitably bent and placed in the channel, its bent ends being 75 driven into the holes 12, 14, thus holding the wire firmly in place.

The wire and channel are preferably so proportioned that the outside surface of the wire is flush with that of the last. A substantially continuous surface is thus formed over which to last the toe, and the last is effectively protected against damage from the blow of the leveling machine roller or from being dropped upon its toe tip. 85

Having described my invention, what I claim as new and desire to secure by Letters Patent of the United States is:

1. A last having a flat metal ribbon extending in a longitudinal vertical plane 90 around the toe tip with its outer surface substantially continuous with the surface of the toe tip.

2. A last having a channel extending in a longitudinal vertical plane around the toe tip, a hole at each end of the channel directed toward the interior of the last, and a metallic wire fitted in the channel and holes. 95

In testimony whereof I have signed my name to this specification.

GUY B. FITZ.
